Bella's Patent. ¹²⁷
Saw Mill. Town of New London County Ct.

~~Letters Patent~~
The subscriber referred to in the Letters Patent, and making part
of the same, Containing a description in the words of the said Letters Patent
of his own improvement in the Mill for Grinding White Lead
Spanish & Paris White, in its dry state.

To all to whom these presents shall come: Be it
known that Bella's Patent of the Town of Groton, County of New
London and State of Connecticut has invented a new and useful
improvement in a Mill for Grinding White Lead, Spanish & Paris
White in its dry state, and that the following is a full and exact de-
scription of the construction and operation of said Mill, as invented
or improved by me.

This mill consists of the following parts viz.
A. Frame made of plank of any convenient width, height &
thickness with a top & bottom to it, with a partition in it just tho
middle as may be seen by a front view of the subjoined drawing
mark, A. & B. this plank frame runs an iron shaft marked
A. on which iron shaft, in one of the apartments between the planks
or frame of said Mill, is hung a Mill Stone of a cylindrical form
and hung on said iron shaft, exactly the same as a common grind
stone is hung on its crank, and calculated to run in the same man-
ner, as will appear by an end view of said Mill & Stone marked
B. this mill stone is to be made of hard granite stone, and the
outer & circumference or surface to be nearly smooth, this mill
stone runs in a bed stone made convex exactly to fit the outer
circumference of the runner as may be seen by an end view of said
bed stone marked C, and extending about one third of the dis-
tance round the runner, under this bed stone is a key made of
wood marked D, the end of which is to key the bed stone close to
the runner (this runner may be of any convenient diameter but
the situation of the place where the mill will be placed on one side
of the mill is a hopper marked E into which the point is put

before it is ground the outer surface of this runner coming in contact with it, carries it through the Mill & discharges it on the opposite side. The front side of this mill is box shaped from the top, down as low as the center of the runner & is close to the surface of the sand, as to prevent any paint from being carried back with its surface. Towards the end of the iron shaft above mentioned in one of the apartments of the frame is a pulley marked E. For a band to run on to low side mill. this mill can be attached to any water or steam power by means of a band only. The upper end of the bed stone of this mill is hung by an iron pin on each side of it marked G.
